UNITED STATES PATENT OFFICE.

CHARLES B. WARRING, OF POUGHKEEPSIE, NEW YORK.

ILLUMINATING-GAS APPARATUS.

Specification of Letters Patent No. 18,216, dated September 15, 1857.

To all whom it may concern:

Be it known that I, CHARLES B. WARRING, of the city of Poughkeepsie, county of Dutchess, State of New York, have invented 5 certain Improvements in the Apparatus for Generating Illuminating-Gas; and I do declare that the following is a full and exact description thereof, reference being had to the accompanying drawings and the letters 10 of reference marked thereon.

To make gas properly it is necessary to know the temperature of the interior of the retort, since if the heat pass from the proper red to a white heat or thereabout the gas is 15 to a certain extent decarbonized, and if the heat fall to a dull red or lower the gas generating material is but partially decomposed, loss ensuing, in either case. The method heretofore employed for ascertaining the 20 temperature of the interior of the retort has been to look at the outside of the retort bottom, which of course is directly over the fire. The light of the fire reflected from the bottom prevents any accuracy, as it easily mis- 25 leads the eye of the observer. My invention remedies this.

It consists of a tube (Figure 1) B B extending from some distance say five or six inches without the retort through the cover, 30 nearly or quite to the bottom thereof. On the upper end there is screwed an eye piece A, which prevents the gas from escaping and at the same time permits the operator to see the bottom of the retort. The part of the 35 tube above the cover prevents the eyepiece from being too much heated by the heat from the retort. The part within is necessary as the cavity of the retort is filled with fragments of hard coal bricks or other materials 40 which would intercept the view of the bottom. It is therefore this combination of tube and eyepiece that I claim.

The eyepiece may be constructed in any way thought best but I prefer the following. 45 A piece of mica or glass is fitted into the larger end of a three quarter reducing coupling such as are used by gas fitters. A short piece of three quarter gas pipe is then screwed down upon it with a little putty, 50 making a gas tight joint. This coupling is then screwed upon the end of a piece of half inch gas pipe which is then screwed into the retort cover.

The gas passes out of the retort through a 55 bent pipe L M, Fig. 1, into cooler or hydraulic main. This heretofore has been

formed of an iron box with a cover secured by bolts and nuts and having its joints made air tight by a packing of putty or rubber or something similar all of which causes much 60 delay and annoyance in putting the same together and in taking it apart. Hydraulic mains for coal gas works are made somewhat differently but have no easy method of inspecting their interior. I form my cooler or 65 hydraulic main thus.

D, Fig. 2, is a cast iron box open at top. On each side a small inward projection a b c d is cast of say four inches in height. Through the bottom a pipe H' G' rising 70 about one inch above the level of the four projections a b c d, serves to carry the gas from the cooler toward the gasometer. W is an inverted siphon to discharge any moisture that may condense in H' G'. e f w' is 75 an inverted siphon the longer leg of which rises to a somewhat less height than H' G'. This serves to carry off the tar and surplus water. h h' serves to empty the box when desired. E is a box of smaller dimensions 80 but of similar form save that the bottom F I J K is placed about three inches from the lower edge. Through this bottom there extends G H from a little above the upper edge down to the level of the lower edge or 85 thereabout. This pipe conveys the gas into the lower box. At h is a hole with a pipe below extending some distance below the lower edges of the box.

When in use the box E is placed in D resting on a b c d. Water is poured into E passing through h into D until it overflows through the siphon. Then close h with a plug and nearly fill E. The water will now stand above the bottom edge of E and thus 90 make a gas tight joint. The pipe L M is made sufficiently large to go freely over H, dipping into the water nearly or quite to the bottom, thus making another gas tight joint. I claim this whole arrangement. The gas 100 now passes through H' G' into the gasometer. This is usually done by carrying a pipe to the bottom of the cistern and thence up through the water to its surface. This requires what is called a dry well for the purpose of removing the condensed water which otherwise would stop the flow of the gas. This dry well is the source of much expense and annoyance. I avoid this by my invention as represented in Fig. 3. In this the 110 gasometer is represented as sunk to the bottom of the water tank or cistern. N O P Q

R T is an iron or metal pipe jointed at O P
Q R (or as many of them as may be necessary). These joints may be formed in various ways but I prefer to make them by
5 screwing the pipe into common elbows used by steam fitters tight on enough to make the joint impervious to gas but allowing the pipes to move as the gasometer rises. The united length of O' P and Q R is a foot or
10 thereabout greater than the maximum height of the gasometer. When therefore the gasometer begins to rise from the inflowing of the gas, R T will be carried up with it and of course go farther from O which is rendered stationary by a fastening at U or by
15 screwing the cooler to the floor of the gas house. The condensed water either flows

into the gasometer or when that rises too high flows back and is discharged by the siphon W''. In order that P Q may always 20 be higher than W'' O N a cord is attached at P' passing over a pulley and having a sufficient weight at the other end.

What I claim therefore is—

1. The eyepiece and tube in combination 25 substantially as described above.
2. I claim the peculiar apparatus above described for conveying the gas into the gasholder.

CHARLES B. WARRING.
